EDGE ROLLER

Martin Leibow, 1052 Creekmere Circle, Dallas, Tex.

Filed Sept. 17, 1964, Ser. No. 81,762

Term of patent 14 years

(Cl. D54—13)

FIG. 1 is a perspective illustrating my design, the rear view of which is like the front; and

FIG. 2, a side elevation.

I claim:

The ornamental design for an edge roller, as shown.
